UNITED STATES PATENT OFFICE

157,949

HORS-D'OEUVRE TRAY

Philip L. Feldman and Julius J. Feldman,
Brooklyn, N. Y.

Application April 24, 1948, Serial No. 145,948

Term of patent 3½ years

(Cl. D44—10)

To all whom it may concern:

Be it known that we, Philip L. Feldman and Julius J. Feldman, citizens of the United States of America and residents of Brooklyn, county of Kings, and State of New York, have invented the new, original, and ornamental Design for an Hors-d'Oeuvre Tray, of which the following is a specification, reference being had to the accompanying drawing, forming part thereof, in which

Fig. 1 is a front elevational view of an hors-d'oeuvre tray, showing our new design; and

Fig. 2 is a plan view thereof.

We claim:

The ornamental design for an hors-d'oeuvre tray, substantially as shown.

PHILIP L. FELDMAN.
JULIUS J. FELDMAN.
